United States Patent Office.

ABNER WHITE, OF MACON, GEORGIA.

Letters Patent No. 100,226, dated February 22, 1870.

IMPROVED HOOK FOR HARNESS.

The Schedule referred to in these Letters Patent and making part of the same.

To all whom it may concern:

Be it known that I, ABNER WHITE, of Macon, in the county of Bibb, and State of Georgia, have invented a certain Improvement in Hooks for Harness; and I do hereby declare that the following is a full, clear, and exact description thereof, reference being had to the annexed drawings making part of this specification, in which—

Figure 1 is a plan view of my invention showing a section of the back-strap, to which the hook is to be secured, showing also the plate of metal and the hook proper.

Figure 2 is a longitudinal vertical section showing all the parts above enumerated together with the button-headed stud, which secures the hook to the metallic plate, the relation of each of the parts to the other being clearly shown.

Figure 3 is a transverse vertical section showing how the head upon the stud projects over and upon the hook, and holds it in position.

Corresponding letters denote corresponding parts in all of the figures.

This invention relates to that class of devices known as back-strap or harness-hooks; and

It consists in combining and arranging the parts of which it is made, as will be more fully described hereinafter.

A, in the drawings, refers to a section of the back strap of a harness, but which may also be supposed to represent a section of a tug or any other portion of a harness, the length of which it is desirable to change with facility, and to which it is desirable to attach a hook.

B refers to a plate or sheet of metal, which is to be about equal in length to the hook itself, and of a width about equal to that of the strap or portion of the harness to which it is to be attached. This plate of metal should be of sufficient thickness to hold firmly the stud, which holds the hook; and it is to be attached by rivets or in some other manner to the strap A of the harness.

C refers to the hook, the construction of which is clearly shown in figs. 1 and 2 of the drawings. The outer crooked end of this part is for the reception of the link of any chain which it may be desirable to attach to it, it being of about the usual form of hooks used for similar purposes. The inner flattened end of this hook is to be reduced in thickness and extended

in width sufficiently to admit of there being formed in it a series of slots or elongated openings, the length of which is to be sufficient to allow the head of the button-headed stud D to pass through them, while their width is only equal to the width of such head, or only enough greater to allow such head to pass freely through them.

D refers to the button-headed stud, the diameter of the rounded portion of which is about equal to the width of its head, and long enough to pass through the plate B, and be secured thereto either by riveting or in any other suitable manner, and yet leave a space between the under surface of the head and the outer surface of the plate equal to the thickness of that portion of the hook through which it passes.

It will be seen that as a consequence of the arrangement of the parts of which this device is composed, means are provided for altering the length of the strap, tug, or other portion of the harness to which it may be attached.

This result may be easily accomplished at any time by unhitching the chain from the hook, and turning it one-fourth of a revolution upon the stud, as an axis, when the elongated head of the stud will be brought in line with the greatest length of the apertures in the hook, and thus the hook will be allowed to pass off from the stud, when by holding it in the same position and passing it in either direction until another slot or aperture is brought over the stud, it may be slipped down thereon, and turned back to its original position, when it will be prevented from separating from the stud by means of the portions of its head which project over upon the face of the hook.

Having thus described my invention,

What I claim, and desire to secure by Letters Patent, is—

A hook for use in connection with harnesses, combining in its construction a plate of metal, B, hook C, and button-headed stud D, arranged substantially as and for the purpose specified.

In testimony whereof, I have signed my name to this specification in the presence of two subscribing witnesses.

his
ANBER X WHITE.
mark.
